Primary Examiner — Cynthia M. Chin*(74) Attorney, Agent, or Firm* — Andrew S. Rapacke(57) **CLAIM**

The ornamental design for an multi-level catamaran, as shown and described.

DESCRIPTION

FIG. 1 is a top front perspective view of the multi-level catamaran, showing the new design;

FIG. 2 is a bottom front perspective view of the multi-level catamaran thereof;

FIG. 3 is a front elevational view of the multi-level catamaran thereof;

FIG. 4 is a rear elevational view of the multi-level catamaran thereof;

FIG. 5 is a left side elevational view of the multi-level catamaran thereof;

FIG. 6 is a right side elevational view of the multi-level catamaran thereof; and

FIG. 7 is a top plan view of the multi-level catamaran thereof; and,

FIG. 8 is a bottom plan view of the multi-level catamaran thereof.

The broken lines are for the purpose of illustrating portions of the article that form no part of the claimed design.
